UNITED STATES PATENT OFFICE

169,230

SET OF CHESSMEN

Lynn L. Wade, Baxter Springs, Kans.

Application August 20, 1951, Serial No. 16,387

Term of patent 7 years

(Cl. D34—5)

To all whom it may concern:

Be it known that I, Lynn L. Wade, a citizen of the United States, residing at Baxter Springs, in the county of Cherokee and State of Kansas, have invented a new, original, and ornamental Design for a Set of Chessmen, of which the following is a specification, reference being had to the accompanying drawing, forming a part thereof.

Fig. 1 is a front perspective view of a set of chessmen, showing my new design; and

Fig. 2 is a side perspective view of the set, the side perspective view of the castle, not shown, being substantially the same as the front perspective view thereof shown in Fig. 1.

I claim:

The ornamental design for a set of chessmen, as shown.

LYNN L. WADE.
